TIRE RACK

Clay D. Lampman, Cuyahoga Falls, Ohio, assignor
to The General Tire & Rubber Company, Akron,
Ohio, a corporation of Ohio

Application April 11, 1952, Serial No. 19,289

Term of patent 14 years

(Cl. D80—10)

To all whom it may concern:

Be it known that I, Clay D. Lampman, a citizen
of the United States of America, residing at
Cuyahoga Falls, in the county of Summit and
State of Ohio, have invented a new, original, and
ornamental Design for a Tire Rack, of which the
following is a specification, reference being had
to the accompanying drawing, forming a part
thereof, in which:

Fig. 1 is a front view of the tire rack showing
my new design; and

Fig. 2 is a perspective view thereof.

The broken lines shown in Fig. 1 are for illustra-
tive purposes only.

I claim:

The ornamental design for a tire rack, as shown
and described.

CLAY D. LAMPMAN.
